UNITED STATES PATENT OFFICE.

GEORGE W. REAM, OF CANTON, OHIO, ASSIGNOR TO THE BUCHER & GIBBS PLOW COMPANY, OF SAME PLACE.

DESIGN FOR A HARROW-FRAME.

SPECIFICATION forming part of Design No. 29,315, dated September 6, 1898.

Application filed August 3, 1898. Serial No. 687,648. Term of patent 14 years.

To all whom it may concern:

Be it known that I, GEORGE W. REAM, a citizen of the United States, residing at Canton, Ohio, have invented and produced a new and original Design for Harrow-Frames, of which the following is a specification, reference being had to the accompanying drawings, forming a part thereof.

In the drawings, Figure 1 is a plan of the harrow-frame, while Fig. 2 is a side elevation thereof.

The leading feature of the design consists of the configuration of the frame, including the parallel bars, the centrally-arranged straight bar, and the irregularly-shaped side bars. A series of harrow-tooth bars A have

their ends out of line, and these ends are covered by side pieces 3, having a configuration following the line of the projecting ends of the bars A. Where these bars project outwardly on one side of the frame they extend inwardly on the other side. In addition to the side bars B there is a central cross-bar C.

What I claim is—

The design for a harrow-frame, as herein shown and described.

In testimony whereof I affix my signature in presence of two witnesses.

GEORGE W. REAM.
